UNITED STATES PATENT OFFICE

159,877

DUMP TRUCK

Marvin E. Whiteman, Los Angeles, Calif.

Application January 14, 1950, Serial No. 7,245

Term of patent 14 years

(Cl. D14—3)

To all whom it may concern:

Be it known that I, Marvin E. Whiteman, a citizen of the United States, residing at Los Angeles, State of California, have invented a new, original, and ornamental Design for Dump Truck, of which the following is a specification, reference being had to the accompanying drawing, forming a part hereof.

Fig. 1 is a top plan view of the dump truck embodying my new design;

Fig. 2 is a view in side elevation of the same;

Fig. 3 is a front view in elevation of the same;

Fig. 4 is a view in side elevation of the same taken from the opposite side from that illustrated in Fig. 2; and

Fig. 5 is a view in rear elevation of the same.

I claim:

The ornamental design for a dump truck, as shown.

MARVIN E. WHITEMAN.
